UNITED STATES PATENT OFFICE.

OSCAR L. CALLAHAN, OF CARTERVILLE, ILLINOIS.

FUEL-ECONOMIZING DEVICE.

1,285,028.

Specification of Letters Patent. Patented Nov. 19, 1918.

Application filed October 14, 1916. Serial No. 125,692.

To all whom it may concern:

Be it known that I, OSCAR L. CALLAHAN, a citizen of the United States, residing at Carterville, in the county of Williamson and 5 State of Illinois, have invented new and useful Improvements in Fuel-Economizing Devices, of which the following is a specification.

This invention relates to fuel economizing devices for internal combustion engines, the 10 object in view being to provide means applicable to carbureters already in use whereby a material saving in fuel is effected, and whereby also the car will be caused to operate with greater smoothness, will start easier 15 in cold weather, and whereby also the accumulation of carbon will be partially eliminated and correspondingly increased power and efficiency imparted to the engine.

20 With the above and other objects in view, the invention consists in the novel construction, combination and arrangement of parts, herein described, illustrated and claimed.

In the accompanying drawing:—

25 Figure 1 is a plan view of a carbureter equipped with the present invention.

Fig. 2 is a side elevation thereof also showing a portion of the intake manifold.

Fig. 3 is a face view of the extension fitting, partly in section.

Fig. 4 is a detail perspective view of the rotary breaker.

Fig. 5 is a similar view of the needle valve arm.

30 Fig. 6 is a similar view of the throttle valve arm.

A designates generally a carbureter body, 1 the outlet neck thereof, 2 the throttle valve operating arm, and 3 the stem of the needle valve by means of which the flow of gasoline or other fuel is regulated within the carbureter.

In carrying out this invention, I employ 45 an extension fitting designated generally at B and comprising a casing 4 which is somewhat elliptical in shape and which corresponds with the shape of the flange 5 of the carbureter body, by which the carbureter is ordinarily fastened to a similar flange 6 at 50 the receiving end of the intake pipe or manifold 7.

The casing of the extension fitting is formed with a bore or cylindrical chamber 8 corresponding in size with and also in alignment with the outlet orifice of the carbureter

proper. Within the chamber or bore 8 is a rotary breaker comprising a preferably vertical shaft 9 and upper and lower sets of wings or blades 10 and 11 radiating therefrom, the upper blades extending preferably 60 at right angles to the lower blades and all of the blades having their outer edges curved to conform and operate in close proximity to the wall of the cylindrical chamber 8. The extension fitting, as shown, is held fixedly between the flange of the carbureter and the flange of the intake manifold and is formed with a downwardly extending opening intersecting the cylindrical chamber 8 and having in connection therewith an auxiliary air inlet valve comprising a valve chamber 12 having an inlet port 13, a valve 15 working within said chamber and being pressed against the valve seat 16 by means of a spring 17. The valve is provided with 70 a stem 18 which extends through the detachable cap 19 on said valve chamber. Said auxiliary air inlet valve opens in proportion to the suction of the engine and operates against the wings of the rotary breaker to 75 impart rotary motion to the latter, said wings having pitched or inclined impact faces 20 against which the inrushing air strikes for the purpose stated. Therefore as the explosive mixture is drawn from the 80 carbureter into the engine, it is churned and atomized by said rotary breaker.

Secured to the operating arm of the throttle valve is an arm 21 and secured to the stem of the needle valve is another arm 90 22 formed with a longitudinal slot 23 to receive the clamping bolt or screw 24 of a clip 25 which is thus adjustable longitudinally of the arm on the needle valve stem. A link 26 has a pivotal connection with the arm of 95 the throttle valve and with said clip on the arm of the needle valve. These arms are so arranged that when the throttle valve is moved toward the open position, the needle valve is also turned in a direction to effect 100 a further opening of the needle valve to admit a larger proportion of liquid fuel. The clip on the arm of the needle valve is made adjustable toward and away from the stem of the needle valve in order to provide for 105 needle valves having finer or coarser threads as is the case in different makes of carbureters. Actual tests and demonstrations have proved that the mechanism hereinabove described gives a very marked improvement 110

in the operation of the engine, due to the fact that the air and fuel are mixed in the proper proportions at different engine speeds and that the mixture is thoroughly 5 churned and broken up or atomized before entering the intake manifold of the engine. Further economy is brought about by the use of the auxiliary automatic air intake valve used in conjunction with the casing of 10 the extension fitting in which the rotary breaker operates. The parts comprised in the present invention may be readily applied to carbureters now in use, being applicable to the carbureter without necessitating any 15 changes or alterations therein.

Changes in the form, proportion and minor details of construction may be resorted to without departing from the prin-

ciple or sacrificing any of the advantages of the invention.

20

I claim:—

An extension fitting insertible between connecting flanges of a carbureter and intake pipe, said fitting being formed with a cylindrical chamber adapted to register with the outlet orifice of the carbureter, and a rotary winged breaker journaled in said chamber and embodying a rotary shaft extending diametrically of said chamber, said fitting being formed with an air inlet opening discharging through the peripheral wall of said chamber and arranged to direct air against the wings of said rotary breaker for imparting motion to the latter.

In testimony whereof I affix my signature. 35
OSCAR L. CALLAHAN.
